WINDOW JACK

Kenneth Dee Scott, Pioneer Hotel, P.O. Box 141,
Elko, Nev.
Filed Dec. 3, 1962, Ser. No. 242,018
2 Claims. (Cl. 182—58)

The present invention is generally related to scaffolding, and more particularly to a novel window jack positionable through an open window and attachable to the frame thereof as well as the surrounding building structure so as to present a working platform on the outer surface of the building adjacent the window. This application is a continuation-in-part of abandoned application Serial No. 163,942, filed January 2, 1962.

During the routine maintenance of a building, the occasion frequently arises for obtaining access to the exterior of a window structure for various purposes such as painting, window washing, or repairs. However, appreciable danger is involved in such operations especially when the particular job being done requires close attention to detail and substantially free access to all portions of the exterior of the window and window frame. While it is appreciated that window washers frequently rely solely upon a safety belt, this means would obviously not satisfactorily provide the stability or range of movement required when repairing or painting the window structure, these operations frequently requiring the provision of extensive and expensive scaffolding.

Accordingly, it is one of the primary objects of the present invention to provide a working platform, portable in nature, which can be simply and quickly installed through a window so as to enable the working on the exterior portions thereof under extremely safe conditions while at the same time providing almost complete freedom of movement.

Another object of the present invention is to provide a portable window jack which is extremely simple in nature and capable of being solidly installed in a matter of minutes so as to make it equally adaptable for use on jobs, such as window washing, which take only a relative short period of time, as well as those jobs requiring extended periods of time.

Likewise, it is an object of the present invention to incorporate a safety or guide rail into the scaffold of the present invention.

Additionally, an object of the present invention is to provide a window jack which, while relatively light in weight thus allowing for the easy turning and positioning thereof, is of a highly stable and durable construction capable of providing the necessary support.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a top plan view of the window jack of the present invention illustrated in an installed position within a window opening;

FIGURE 2 is an elevational view of the window jack looking from the inside end thereof;

FIGURE 3 is a cross-sectional view taken substantially on a plane passing along line 3—3 in FIGURE 1;

FIGURE 4 is a partial cross-sectional view taken substantially on a plane passing along line 4—4 in FIGURE 1;

FIGURE 5 is a cross-sectional view taken substantially on a plane passing along line 5—5 in FIGURE 1; and

2

FIGURE 6 is a perspective view of the foldable and removable guard rail.

Referring now more particularly to the drawings, reference numeral 10 generally designates the window jack comprising the present invention. This window jack 10 consists of a flat working platform 12, preferably of wood, attached by fastening means such as screws 14 to two parallel elongated subjacent support or frame members 16. These frame members 16 are preferably channel-shaped with the bight portion being orientated horizontally for the threaded reception therein of the fastening means 14.

As will be appreciated from FIGURES 1 and 2, the working platform 12 is narrowed at two points so as to form, along both edges thereof, two abutment shoulders 18 and 20 for engagement with either the window frame 22, the exterior surface of the building 24, or both as shall be gone into in more detail presently.

Extending transversely of the frame members 16 and rigidly affixed to the inner end thereof is an angle member 26, the ends of the angle member 26 extending laterally beyond the edges of the inner reduced portion of the platform 12. Mounted on each of the laterally extending ends of the angle bar 26 is an extension member 28 laterally adjustable by means of a longitudinal slot 30 therethrough. This lateral adjustment is required so as to adapt the window jack to various widths of window openings, each extension member 28 being fixed in a laterally adjusted position by means of a bolt 32 freely received through the slot 30 and threaded within a suitable aperture within the bar 26 so as to effectively clamp the extension member 28 to the bar 26 thus preventing movement therebetween.

The outer portion of each extension member 28 has an adjusting bolt 34 extending transversely therethrough and provided with an abutment member 36 on its inner end for engagement with the inner surface of the window frame 22 thus causing an inward movement of the platform 12 so as to engage either the shoulder 20 with the window frame 22 or the shoulder 18 with the exterior building surface 24, or both, depending upon the relative width of the window frame and building wall. The abutment member 36 is to be provided with a suitable non-scratching surface 38 so as to avoid a marring of the window frame 22, the adjustment of this member 36 being accomplished by rotating the adjusting bolt 34 through an internally threaded nut 40 affixed to the inner surface of the extension member 28 and in line with a suitable aperture therethrough for the passage of the bolt 34.

In addition to the use of the adjustable abutment members 36 as a means for stabilizing the inner end of the jack 10 and engaging the shoulders 18 and 20, an adjustable elongated rod 42 is provided for engagement beneath the inwardly extending overhanging window sill 44, this rod 42 being of a length substantially equal to the width of the inner portion of the platform 12. In order to effect the upward and outward adjustment of the rod 42 for engagement beneath the sill 44, two brackets 46 are provided, both secured to the angle member 26 in line with the support members 16 by any suitable means such as screws 48. Each bracket 46, extending inwardly from the inner end of the platform 12, consists of a horizontal upper portion 50, a vertical portion 52 depending from the inner end thereof, and a third portion 54 extending upwardly at an angle from the lower end of the vertical portion 52 to abutting engagement with the vertical leg of the angle member 26 for attachment thereto. Rigidly affixed to the vertical member 52 within the bracket 46 is a brace member 56 presenting a flat

bearing surface 58 orientated perpendicular to the path of travel desired for the rod 42. Aligned apertures are provided through the depending portion 52, bracing member 56, and upwardly angled portion 54 parallel to the afore-mentioned line of travel with a tubular sleeve 60 being fixedly positioned within the aperture through the portion 54 and with a rotatable sleeve 62 being maintained for rotation through the apertures in the portion 52 and member 56 by an annular shoulder 64 integral with the sleeve 62 and slidably engageable with the bearing surface 58 of the member 56. The rod 42 has two threaded rods 66 rigidly affixed thereto with each rod extending through the aligned sleeves 60 and 62 of the adjoining bracket 46, this rod 66 being threadedly received within an internally threaded nut 68 integral with the rotatable sleeve 62 whereby by the rotation of the sleeve 62, a suitable handle means 70 being provided, a longitudinal movement of the threaded rod 66 is effected, this rod being freely guided by the sleeve 60, thus resulting in an engagement of the rod member 42 beneath the sill 44 so as to effect the desired inward movement of the platform 12 to assist the adjustable abutment members 36 in securing the platform to the window structure.

In addition to the adjustable abutment members 36 provided on the outer ends of the extension members 28 and the adjustable clamping means mounted by the brackets 46, the window jack 10 also includes a supporting horse structure 72 incorporating means for adjustably engaging an external window ledge 74. This horse structure 72 consists of two depending panels 76 secured to the frame members 16 by bolts 78, the lower edge 80 of each panel being angled so as to substantially conform to the upper surface 82 of the ledge 74. Extending transversely of the plates 76 and secured to the ends thereof by driven fasteners 84 are beams 86, 35 the lower edges of which are angled so as to conform with the slope of the bottom edge 80 of the plates 76, form in conjunction with the plates 76 the supporting horse structure 72. However, in order to compensate for variances in building construction, the horse 72 is provided with adjustable means so as to insure a proper levelling of the platform 12. This adjusting means consists of four elongated threaded bolts 88 each having a bearing head 90 at the lower end thereof for engagement with the upper surface 82 of the ledge 74, these adjustable bolts 88 being threadedly received within internally threaded sleeves 92 fixedly secured within the beams 86 in line with the superjacent supporting members 16. Also, the present invention contemplates the provision of additional plates 94 secured to the frame members 16 by bolts 96 and shaped so as to engage the upper surface of the portion of the window casing adjacent the ledge 74 upon a retraction of the adjustable bolts 88 to their innermost position thus resulting in an even more stable structure.

So as to insure the safety of the worker on the platform, the present invention also includes a removable and foldable guard rail 98 capable of being easily inserted through a window opening and subsequently unfolded and secured to the platform 12 about the outer periphery thereof. This guard rail 98 consists of a central U-shaped section 100 having two vertical legs 102 and suitable cross braces 104, and two end sections 106 each including a vertical leg 108 and horizontal braces 110 extending therefrom and terminating in vertically orientated sleeves 112 rotatably receiving the vertical legs 102 therethrough thus allowing a pivoting of the end sections 106 against the main or central section 100 resulting in a compacting of the guard rail 98.

The guard rail structure 98 is mounted on the platform 12 by a positioning of the lower ends of the legs 102 and 108 within upwardly opening sockets 114 appropriately positioned about the outer edge of the platform 12, these legs 102 and 108 being fixed within the sockets 114, if so desired, by suitable means such as set screws 116.

From the foregoing, it is considered to be readily apparent that a novel simplified window jack structure has been defined with this structure providing a stable horizontal working platform exterior of a building window 5 with the stability of the platform being maintained by a support horse engageable with the window ledge and including adjustable legs thereon, two adjustable abutment members for engagement with the edges of the window frame on the interior of the building so as to draw the platform inwardly thus resulting in an engagement of abutting shoulders on the platform with the exterior surface of the window frame or building so as to provide for a clamping between the shoulders and the adjustable abutment members, and additional clamp means capable of adjustable engagement with the undersurface of the normally provided inwardly projecting window sill so as to result in a clamping of the jack to the window sill with this clamping engagement also assisting in providing the rigid engagement of the afore-mentioned shoulders with the exterior of the window frame or building itself. Accordingly, it will be recognized that the aforementioned structure results in the provision of a relatively simply constructed portable window jack capable of being quickly and safely set up so as to accommodate a worker allowing a maximum freedom of movement with a minimum risk involved.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A window jack for use in conjunction with a building window having a window frame, a sill extending inwardly of the frame so as to present an overhanging shoulder and a window ledge projecting outwardly from said frame, said jack consisting of a working platform, said platform being positionable through said window frame so as to project inwardly and outwardly thereof, first means on the inner edge of said platform for engagement upwardly at an angle beneath said overhanging shoulder, second means on said inner edge laterally adjustable for engagement with the inner surface of the window frame at opposite edges of the window, and means depending from said platform and engageable with the ledge for the support of the platform thereover, said first means including an elongated transversely extending rod of a length generally equal to the width of said inner edge, and adjusting bolts adjacent each end of said rod for moving said rod into engagement beneath said overhanging shoulder, said second means also being adjustable outwardly relative to the window frame so as to draw the platform inwardly, the portion of said platform outwardly of said frame being of greater width than said frame and tightly engageable therewith upon an inward drawing of the platform by the adjustable second means.
2. A window jack for use in conjunction with a building window having a window frame, a sill extending inwardly of the frame so as to present an overhanging shoulder, and a window ledge projecting outwardly from said frame, said jack consisting of a working platform, said platform being positionable through said window frame so as to project inwardly and outwardly thereof, first means on the inner edge of said platform for engagement upwardly at an angle beneath said overhanging shoulder, second means on said inner edge laterally adjustable for engagement with the inner surface of the window frame at opposite edges of the window, and means depending from said platform and engageable with the ledge for the support of the platform thereover, said first means including an elongated transversely extending

rod of a length generally equal to the width of said inner edge, and adjusting bolts adjacent each end of said rod for moving said rod into engagement beneath said overhanging shoulder, the opposite side edges of the platform including two laterally aligned pairs of stepped portions forming a first pair of shoulders engageable with the window frame and a second pair of shoulders engageable with the exterior of the building, said second means being adjustable outwardly relative to the window frame so as to effect an inward drawing of said platform and an engagement of at least one of said pairs of shoulders.
